FACE PLATE FOR PLUMBING FIXTURES
OR THE LIKE

William Taylor, 2222 Malcolm Ave., Los Angeles, Calif.,
and Nathan Holzberg, Los Angeles, Calif.; said Holz-
berg assignor to said Taylor

Filed Nov. 19, 1962, Ser. No. 72,529

Term of patent 14 years

(Cl. D91—3)

FIG. 1.

FIG. 2.

FIG. 3.

FIG. 4.

FIG. 1 is a front elevational view of a face plate for plumbing fixtures or the like, showing our new design;
FIG. 2 is a side elevational view thereof;

FIG. 3 is a front elevational view of another embodiment of the design shown in FIG. 1 wherein the outline is oval shaped and parts of the interior ornamentation conform to said oval; and

FIG. 4 is a side elevational view thereof.

The rear of both forms of design, not shown, are flat and plain except for the opening areas.

We claim:

The ornamental design for a face plate for plumbing fixtures or the like, as shown and described.
